JOSEPH W. LEGG, OF WILKINSBURG, PENNSYLVANIA, ASSIGNOR TO WESTINGHOUSE ELECTRIC & MANUFACTURING COMPANY, A CORPORATION OF PENNSYLVANIA.

CIRCUIT-INTERRUPTER SYSTEM.

Application filed December 13, 1920. Serial No. 430,155.

My invention relates to circuit-interrupting devices and particularly to electric valves for interrupting currents of relatively high values.

5 One object of my invention is to provide an electric circuit-interrupting valve comprising a metal casing in combination with an arc-extinguishing auxiliary circuit and means for compensating for the inductive effect of the casing when the circuit is interrupted.

Another object of my invention is to provide an electrical system that shall employ an electric valve as a circuit interrupter 15 therefor and means for preventing re-establishing the valve arc by reason of the inductive character of the interrupting circuit; and that shall permit of the use of a relatively small condenser to extinguish the 20 valve arc.

Heretofore, it has been usual to employ electric valves of the mercury-vapor type to interrupt circuits of relatively low current values. Such valves have usually employed glass bulbs or containers which, of themselves, added no inductance to the circuits to which they were connected. It is desirable, if not imperative, in connection with circuits carrying currents of relatively 30 high values, to employ so-called metal-case valves which have metal containers in lieu of glass bulbs. A metal container introduces a very undesirable inductive effect into a circuit, when utilized as an element 35 of an interrupter.

In practising my invention, I provide a metal-case valve connected in series in a main circuit to function as an interrupter therefor and a local condenser circuit 40 adapted to discharge a current in opposition to the valve arc diverting the current from the arc path to quench the latter and to, thereby, interrupt the main circuit.

A conductor, forming a part of the condenser circuit, is closely coupled with the field of the valve current in order to permit a diversion of the current from the valve circuit to the condenser circuit without substantially changing the magnetic-field conditions in the surrounding space. A resistor is so related to the valve as to permit a discharge of the stored energy of the circuit in order to prevent the re-establishing 50 of the valve arc by reason of an excessive rise of voltage across the valve terminals.

Figure 1 of the accompanying drawings is a diagrammatic view of an electric system and an electric valve embodying my invention.

Fig. 2. is a diagrammatic view of a usual 60 arrangement, with an electrical valve and a condenser connected across the terminals thereof outside the casing, and

Fig. 3 is a simplified diagram of the system shown in Fig. 1. 65

A system embodying my invention, may comprise, in general, a direct-current generator 1, a trolley, or other supply, conductor 2 that is connected to the generator 1 through an electric valve 3 and a conductor 4, a 70 series transformer 5, a relay 6, a condenser 7, a charging resistor 8 for the condenser 7, a resistor 9, a circuit interrupter 10, a return-line conductor or track 11 and a load or electric vehicle 12. 75

The condenser 7 and its charging resistor 8 are connected between the positive and negative terminals of the generator 1, through a conductor 13, a conductor 14, the resistor 9, the interrupter 10, an actuating coil 15 of 80 the interrupter 10, a conductor 16 and a conductor 17, to the conductor 4.

The valve 3 comprises a metal casing 18 that is connected to the positive line conductor 2 by a connector 19 and is insulated from the ground by insulators 20. The upper end of the casing 18 is provided with a flange 21 for the reception of a depending flange 22 of a cover plate or member 23. The flanges 21 and 22 are hermetically sealed, as by a ring 90 24 of wax or other material. The cover plate 23 is provided with a central aperture 25 and a countersunk portion 26 to provide a shoulder 27. A hollow insulating bushing 28 having an enlarged upper portion 29, disposed in the countersunk portion 26, is supported on the shoulder 27 and has a reduced end portion 30 extending through the aperture 25 into the casing. 95

An anode 31 comprising a water cooled 100 jacket 32 extends through, and is supported by, the bushing 28 in which a nut 33, supported on a shoulder 34 in the bushing, and the water jacket 32 are hermetically sealed, as by a sleeve 35 of wax. The upper end of 105 the water jacket 32 constituting the anode 31 is connected, by nuts 36 and a terminal connector 37, to the conductor 4.

A conductor 38, extending through the aperture 25 and having its lower end 39 sub- 110

merged in a mercury cathode 40 at the bottom of the casing 18, is connected, by a connector 41, to the conductor 14, at a point between the resistor 9 and the condenser 7, 5 and is provided with a washer or ring portion 42 surrounding the bushing 28. The ring portion is insulated from the cover plate 23, and the opening 25 is hermetically sealed by a body 43 of suitable insulating material.

10 The series transformer 5, for which the conductor 4 constitutes the primary element, comprises a core member 44 and a secondary winding 45 that may be connected, through 15 a spark gap 46 and a conductor 47, to the terminals of an actuating coil 48 of the relay 6. A pivoted arm 49 is adapted to be actuated, in response to energization of the relay coil 48, to cause the engagement of contact 20 members 50 that are connected, by the conductor 17 and a flexible conductor 51, between the conductor 4 and a terminal 52 of the condenser 7.

25 Fig. 2 shows the usual method of connecting a condenser across an electric valve. With the condenser 7 connected across the outside of the valve 3, to interrupt the circuit, the collapsing magnetic flux surrounding the current path, especially in the iron 30 casing 18, will oppose the decrease of the current in the valve, making it very difficult to quench or interrupt the valve-arc.

35 In accordance with my invention and as shown in Figs. 1 and 3, the main-circuit current and the condenser current pass through the casing 18 in the same direction, as indicated by arrows 57 and 58, respectively. In this case the flux induced by the current in the valve path 31, 40 is substantially identical with the flux induced by the current in the conductor 38 of the condenser circuit and the transfer of the current from the valve path to the condenser circuit takes place readily with the magnetic-flux conditions remaining practically unchanged. With such organization a relatively small condenser is sufficient to quench the valve arc.

40 In operation, by reason of the spark gap 46 in the relay-circuit, ordinary load fluctuations will not affect the system. In response to a predetermined rate of change of load current, or in response to a short circuit across the generator, a spark will jump the gap 46 to energize the relay coil 48. This 45 action will operate the relay arm 49 to close the contact member 50, whereupon, the condenser circuit will be connected in parallel to the valve-arc path between the positive line conductor 4 and the mercury cathode 40. 50 The condenser discharges in opposition to the arc current, diverting the line current from the arc path to the condenser conductor 38, such action not being opposed by the surrounding magnetic field, as explained 55 above. The diversion of the line current to

the condenser circuit will interrupt the main circuit connection through the mercury-arc valve, leaving only an auxiliary discharge resistor 9 connected in parallel to the valve to permit a discharge of the stored energy of 70 the circuit. The relatively-slow-acting interrupter 10 will now operate to fully clear the main circuit by opening the circuit through the shunting resistor 9.

75 The shunting resistor 9, however, remains connected in parallel to the valve gap for a sufficient time after the operation of the sensitive relay 6 to provide a discharge path for the current induced by the field surrounding the current paths within the valve when the 80 field finally collapses, after the condenser has finally stopped the current flow in the line, thus preventing the development of high voltages and the danger of arc-reignition.

85 The arrangement whereby the resistor 9 prevents high-voltage surges across the valve and whereby the conductor 38 conducts the condenser current through the casing 18 in the same direction in which the main-circuit current passes, so relieves the main arc path 90 and the condenser circuit of inductive opposition as to require the condenser to be of only sufficient capacity to overcome the potential drop across the valve to permanently open the main circuit. 95

While I have shown and described a particular form of my invention, it is equally applicable in connection with other devices where the field interlinked with the interrupting circuit hinders the interruption of the current.

I claim as my invention:—

1. A circuit-interrupting system comprising a circuit, an electric valve disposed therein and having inductive characteristics, 105 means for momentarily diverting the current from the valve to extinguish the valve arc, means for reducing the inductive effect of the valve during the interruption of the current therethrough and means for reducing inductive effects of the valve during the interruption of the current in the circuit. 110

2. A metal-case electric valve having main circuit terminals, a condenser having its circuit connected to discharge across the valve, 115 said condenser circuit being so related to the casing that the decrease of the valve current does not substantially change the magnetic flux conditions in the surrounding space, and means for preventing a surge of 120 induced current upon the interruption of the current through the main circuit.

3. The combination with an electric valve comprising a metal casing, an anode insulated with respect to the wall thereof, a 125 body of mercury therein constituting the cathode thereof, circuit and terminals connected to the anode and to the cathode, of a conductor leading in said casing parallel to the discharge path between said anode and 130

said cathode, a condenser means connected in circuit with said conductor, and means for connecting said condenser and said conductor between said cathode and said anode.

5 4. The combination with an electric valve comprising a metal casing, an insulating bushing in a wall thereof, an anode extending into the casing through the bushing, and a mercury cathode in the casing, of a 70
10 conducting member surrounding the bushing and insulated from said casing, said member having a portion extending to the cathode, a condenser, and means for connecting said condenser between the anode and 75
15 said conducting member.

5. An electrical device comprising a magnetizable wall portion, a main circuit terminal member extending through said wall portion and insulated therefrom, an auxiliary terminal member extending through 80
20 said wall portion adjacent to said main circuit terminal member and insulated from both said wall portion and said main circuit terminal member, a means for discharging a current through said auxiliary terminal member to momentarily divert the 85
25 normal current flow from said main circuit terminal member, said means being so connected that the current discharge does not 90
30 substantially affect the magnetic flux interlinked with said terminal members.

6. An electrical device comprising a magnetizable wall portion, a main circuit terminal member extending through said wall portion and insulated therefrom, an auxiliary terminal member extending through 95
35 said wall portion adjacent to said main circuit terminal member and insulated from both said wall portion and said main circuit terminal member, a condenser means for 100
40 discharging a current through said auxiliary terminal member to momentarily divert the normal current flow from said main circuit terminal member, said condenser means being so connected that the current discharge 105
45 does not substantially affect the magnetic flux interlinked with said terminal members.

7. An electric valve having a pair of main terminal members, the flow of current 110
50 through said main terminal members inducing an appreciable magnetic flux in the surrounding space, an auxiliary terminal member adjacent to one of said main terminal members, a condenser means for discharging a current through said auxiliary terminal member to momentarily divert the 115
55 current from the adjacent main terminal member and interrupt the valve circuit, said condenser means being so connected that the interruption of the current in the valve circuit does not substantially affect the magnetic flux conditions in the surrounding 120
60 space.

8. A mercury-arc electric valve having a 125
65 pair of discharge terminals, the flow of cur-

rent through said discharge terminals inducing an appreciable magnetic flux in the surrounding space, an auxiliary terminal member adjacent to one of said discharge terminals, a condenser means for discharging a current through said auxiliary terminal member and the other of said discharge terminals to momentarily divert the current from said one of said discharge terminals and interrupt the valve circuit, said 75
condenser means being so connected that the interruption of the current in the valve circuit does not substantially affect the magnetic flux conditions in the surrounding 80
space.

9. The combination with a power line, of a circuit interrupter, a casing therefor having a magnetizable wall portion, a pair of oppositely disposed main terminal members for said circuit interrupter, at least one of said main terminal members extending through said wall portion and insulated therefrom, the flow of current through said main terminal members inducing an appreciable magnetic flux in said magnetizable 90
wall portion, an auxiliary terminal member extending through said magnetizable wall portion adjacent to said one of said main terminal members, said auxiliary terminal member being connected, inside said casing, 95
to the other of the main terminal members, an external circuit including a condenser connected to said auxiliary terminal member, means for causing the current to be interrupted in said circuit interrupter and 100
momentarily transferred to said condenser circuit whereby the magnetic flux conditions in said casing are substantially unaltered during the interruption of said circuit-interrupter current, and means for providing 105
a discharge path for the current induced by the change in the magnetic flux conditions subsequently to the transfer of the current to said condenser circuit.

10. An electric-discharge valve having a 110
pair of discharge electrodes, a condenser, means for discharging said condenser through the path between said electrodes to interrupt a discharge therethrough, an auxiliary discharge path connected in shunt 115
to said electrodes, and means responsive to the interruption of the circuit through said valve for opening the circuit through said auxiliary discharge path.

11. An electric-discharge valve having a 120
pair of discharge electrodes, a condenser, means for discharging said condenser through the path between said electrodes to interrupt a discharge therethrough, a resistor connected in shunt to said electrodes, 125
and means responsive to the interruption of the circuit through said valve for opening the circuit through said resistor.

12. A mercury-arc valve comprising a 130
metallic envelope, a mercury cathode, an

anode, an auxiliary conductor disposed in said casing parallel to the discharge path between said cathode and said anode, and means for diverting the current from the discharge path to said conductor.

13. A space-current discharge device of a type adapted to sustain its discharge by the passage of the space current itself, said device comprising a magnetizable metallic casing, an anode and a cathode, main terminals for said anode and said cathode, respectively, an auxiliary terminal adjacent to one of said main terminals, an auxiliary conductor inside said casing connecting said auxiliary terminal with the other main terminal inside said casing, and external circuit connections for diverting the main current to the auxiliary terminal and the auxiliary conductor from the adjacent main terminal and the space-current discharge path within the casing.

14. A space-current discharge device of a type adapted to sustain its discharge by the passage of the space-current itself, said device comprising a magnetizable metallic casing, an anode and a cathode, main terminals for said anode and said cathode, respectively, an auxiliary terminal adjacent to one of said main terminals, an auxiliary conductor inside said casing, connecting said auxiliary terminal with the other main terminal inside said casing, and external circuit connections for connecting a condenser between said auxiliary terminal and the adjacent main terminal, said condenser drawing a sufficiently large charging current to divert the main current from the space-current discharge path within the casing.

In testimony whereof, I have hereunto subscribed my name this 3rd day of December, 1920.

JOSEPH W. LEGG.
